UNITED STATES PATENT OFFICE.

WILLIAM TAYLOR AND FRANCIS WILLIAM PRESTON, OF LEICESTER, ENGLAND.

METHOD OF AND APPARATUS FOR POLISHING.

Application filed February 21, 1922. Serial No. 538,283.

This invention relates to a method and apparatus for polishing, and more specifically for polishing glass and like substances, and aims to provide a method and means whereby more efficient and economical polishing may be secured through suitable regulation of the amount of polishing material maintained between the coating surfaces of a polishing member and the work.

10 In machines customarily used for polishing glass in which a relative movement is effected between the coating surfaces of a polishing member and the work, the polishing is accomplished by means of an abrasive powder, such as rouge, which is supplied so as to enter between the polishing member, the face of which may consist of felt or other suitable material, and the surface to be polished. The abrasive is customarily 15 suspended in a liquid vehicle, or lubricant, such as water, and sometimes part of the water is supplied separately.

The efficiency of the polishing depends upon the amount of abrasive material and 20 amount of water or other lubricant present between the polisher and the work. The amount of abrasive and amount of lubricant present also determine the frictional resistance between the coating surfaces of the work and polishing member. In general, so 25 long as the amount of liquid present is suitable, increase in the amount of abrasive present increases the friction, while too little abrasive decreases the rate of polishing and 30 decreases the friction. On the other hand, in general, decrease in the amount of liquid between the polisher and the work increases the friction, while increase in the amount of liquid reduces the friction. It is generally 35 necessary to limit the friction not to exceed a predetermined maximum in order to avoid 40 displacement of the work or for other reasons. In order to obtain the most efficient polishing, having regard to the rate of 45 polishing, power consumption, and consumption of abrasive, the frictional resistance between the polishing member and the work should be maintained at all times 50 during an operation as near as may be to such maximum, and it may in practice be allowed to vary within a predetermined range below said maximum. To this end the supplies of abrasive and lubricant must 55 be maintained within suitable limits.

55 In an application of William Taylor, filed

May 17, 1919, Serial No. 297,777, there is described and claimed a method and apparatus wherein the supply of lubricant or abrasive is regulated according to variations in frictional resistance between the coating surfaces of the polishing member and the work in order to maintain the frictional resistance substantially constant or within a limited range of variation. Said application also describes and specifically claims a method and means wherein the above result is secured by causing the variation of frictional resistance between the surfaces of the work and polishing member to automatically control and vary the supply of lubricant or abrasive and abrasive.

In some cases it is convenient not to have the action automatic throughout, and according to the present invention the variations of traction are caused to effect the operation of a suitable indicating means, and an operator controls manually the supply of lubricant or abrasive, or both, in accordance with the indications of such indicating means. The indicating means is most desirably a recording device whereby a continuous record or graph of the frictional resistance during the whole polishing operation or so much thereof as may be desired is provided. Such a record gives more information as to the condition of the polishing material between the coating surfaces than a nonrecording indicator.

The apparatus features of the invention may be incorporated in glass polishing machines of many different types. For the sake of illustration, however, we have in the accompanying drawings illustrated the application of the invention to a known type of polishing machine which is used for the polishing of plate glass. A full understanding of the invention considered from both its method and its apparatus sides can best be given by a description of the illustrative machine shown in the drawings and the operation and use thereof.

In the drawings: Fig. 1 is a sectional plan view of a plate glass polishing machine incorporating the apparatus features of the invention and adapted for use in practicing the method, the view being taken on line 1-1 of Fig. 2; Fig. 2 is a view of the machine in elevation with parts in section and parts omitted; Fig. 3 is a view on a larger

scale of one of the recorder operating levers; Fig. 4 illustrates a graph made by one of the recorders; and Fig. 5 is a fragmentary view showing another form of indicating means.

The machine shown in the drawings comprises a circular horizontal work holding table 10 on which the plate or plates A to be polished are placed and suitably secured, 10 as by means of plaster of Paris and pegs in the usual manner. The table is mounted on a vertical shaft 11 and is rotated by a driven gear 12 meshing with a gear 13 on the shaft 11. A plurality of polishing members or units are mounted above the table each comprising a rotatable frame or spider 15 carried on the lower end of a vertical shaft 16. Each frame carries a plurality of rotatable disc shaped felt covered polishing blocks 17 each carried on the lower end of a spindle 18 rotatably and slidably mounted in the frame so that the blocks may rest on the surface to be polished when the machine is in operation. The spindles 18 are provided with means for limiting their downward movement when the frame is raised or the table is lowered. Four such polishing members or units are customarily provided as shown and are of different sizes carrying 30 different numbers of blocks 17, the larger unit extending from slightly beyond the edge to past the center of the table. Upper and lower bearings for each frame shaft 16 in which the shaft is free to turn are provided in fixed framework extending over the table. The upper bearings are carried by a cross beam 20, the upper bearings for two of the frame shafts being mounted on the cross beam and the upper bearings for the 40 other two shafts being mounted on rigid extensions from the cross beam 20. The lower bearings are carried by a cross beam 21.

Such machines are customarily provided with means for supplying abrasive and lubricant, usually rouge and water, to the surface of the glass, the supply usually being continuous during the polishing operation and at an arbitrary rate dependent on the operator's judgment. In operating in 50 this way the most efficient polishing is not obtained.

In the machine shown, the construction is such that when the frictional resistance between the work and the polishing blocks of 55 any one of the polishing members or units exceeds a predetermined value a yielding part will be moved to effect the operation of an indicating device. For this purpose, as shown, the lower bearing 25 of each of the 60 shafts 16 is carried by an arm 26 which extends in a direction which is radial from the axis of the table and is elastic and slightly flexible, so that the bearing 25 is capable of a slight movement against the elastic 65 resistance of the arm 26 in the direction of

the movement of the portion of the table 10 directly below the bearing. Such movement of the bearing or arm controls the operation of a device for indicating variations in the strain on the bearing and, therefore, 70 variations in the frictional resistance between the polishing members and the work. As shown in Figs. 1, 2 and 3, and most desirably, the indicators are recording devices 75 30, which may be of any suitable form for marking a record or graph of the varying frictional resistance on a moving web or other sheet, and the stylus arm 31 of each of which is operatively connected to be operated by the movement of one of the bearings 25.

The rouge and water are supplied for each polishing member or unit through a discharge nozzle or pipe 35 controlled by a manually operable valve 36 and leading off 85 most desirably from a supply pipe 37 in which the polishing material is kept in circulation.

The operation is as follows: The table 10 being in rotation, the friction between the plate A on the table and the polishing blocks 17 because of the varying rate of movement of the work at different distances from the axis of the table causes each of the polishing blocks to rotate on its spindle and at the same time causes each of the frames 15 forming with its group of polishing blocks one of the polishing members or units to rotate about its shaft 16. The friction between the work and the blocks also tends to move each polishing member in the direction in which the table moves beneath such member, and this drag on the member causes a stress on its lower shaft bearing 25 in the direction of movement of the table beneath the bearing. This stress causes a slight movement of each of the bearings 25 against the elastic resistance of its supporting arm 26, the amount of which movement varies according to the amount of frictional resistance between the polishing member and the work. Such movement of the bearing is recorded by its recording device 30, and the supply of polishing material is manually regulated through the valve 35 in accordance with the 100 variation in such frictional resistance as shown by the recording device. For example, if the recording device shows that the frictional resistance has increased above a predetermined value, the supply of polishing material will be turned on or increased by the operator, and as the frictional resistance is shown to decrease again or reaches a predetermined lower limit, the supply is diminished or cut off. Or again if the graph is of 110 the character shown in Fig. 4, in which as the polisher becomes dry the frictional resistance increases up to a point X, falls off somewhat at Y and then increases at Z, it 115

may indicate that the polisher has become 120 dry. Or again if the graph is of the character shown in Fig. 5, in which as the polisher becomes dry the frictional resistance increases up to a point X, falls off somewhat at Y and then increases at Z, it 125 may indicate that the polisher has become 130

overloaded with rouge and accordingly the operator will diminish the supply of rouge and increase the supply of water.

Fig. 5 shows a non-recording indicating means supplied to the slightly movable lower bearing of one of the shafts 16. The indicating means here shown is electrical and comprises a lamp or bell 40 and a source of current 41. The lamp or bell 40 and the source of current are connected so that the circuit through them may be completed by an adjustable circuit closing device operated by the movement of the bearing 25 when the frictional resistance between the polishing member and the work reaches a predetermined value. An additional lamp or bell 43 may also be provided, the circuit through which is closed by a circuit closing device 44 operated by the bearing 25 when the frictional resistance is decreased to a predetermined lower value. The circuit closing devices are adjustable for varying the resistance value at which each will be operated. From the indications given by such signal devices the supply of polishing material may be regulated by the operator to maintain the frictional resistance substantially constant or within a desired limited range.

As the polishing material is distributed more or less evenly over the work on the table 10 by the rotation of the table and the polishing members the polishing material may be supplied to the work at a single point, and this single supply may be regulated in accordance with indicating means controlled according to the frictional resistance between the work and any one of the polishing members.

Controlling or varying the supply of polishing material, as such expressions are used herein, include controlling or varying the rate of supply of the polishing material as a whole when composed of abrasive and lubricant or of either component thereof.

What is claimed is:

1. The method of controlling the supply of polishing material in polishing a surface by means of a polishing member, said polishing member and the work being moved relatively to one another to effect the polishing, which method comprises utilizing the variation of frictional resistance between the surfaces of the work and polishing member to cause the operation of an indicator, and manually varying the supply of polishing material according to indications of the indicator.

2. The method of controlling the supply of polishing material in the polishing of a surface by means of a polishing member, said polishing member and the work being moved relatively to one another to effect the polishing, which method comprises utilizing the variation of frictional resistance between the surfaces of the work and

the polishing member to make a continuous record of the variation in the friction, and manually controlling the supply of polishing material according to said record.

3. The combination with a polishing machine having cooperating work-holding and polishing members and means for causing relative motion between said members for producing relative movement between the coacting surfaces of the polishing member and the work, of means for supplying polishing material to said surfaces, manually operated means for controlling the supply of polishing material, an indicator, and means operated by variation of the friction between said surfaces to cause the indicator to indicate to an operator of the controlling means when the friction between said surfaces reaches a predetermined value.

4. The combination with a polishing machine having cooperating work-holding and polishing members and means for causing relative motion between said members for producing relative movement between the coacting surfaces of the polishing member and the work, of means for supplying polishing material to said surfaces, a recorder, and means operated by variation in the friction between said surfaces to cause the recorder to make a continuous record of the variation of such friction.

5. The combination with a polishing machine having cooperating work-holding and polishing members and means for causing relative motion between said members for producing relative movement between the coacting surfaces of the polishing member and the work, of means for supplying polishing material to said surfaces, manually operated means for controlling the supply of polishing material, a recorder, and means operated by variation in the friction between said surfaces to cause the recorder to make a continuous record of the amount of said friction, the recorder being positioned so that the record being made thereby is visible to an operator of said controlling means.

6. In a polishing machine, comprising a polishing member, a work-holding member, and driving means for moving one of said members to cause relative movement between the coacting surfaces of the polishing member and the work, indicating means for indicating variations in the friction between the said surfaces actuated by such friction independently of other components of the load on said driving means.

7. In a polishing machine, comprising a polishing member and a work-holding member, means for moving one of said members and means for constraining the other of said members against movement by the friction between the coacting surfaces of the polishing member and the work, the com

- 5 bination of a yieldable element in said con-
straining means adapted to yield when the
said friction reaches a predetermined value,
and indicating means actuated by the yield-
ing of said yieldable element.
8. In a polishing machine, comprising a
work-holding member, a plurality of polish-
ing members, means for causing a relative
movement between the work and the polish-
ing members, and an indicator for each
polishing member adapted to indicate to the
operator when the friction between such
polishing member and the work reaches a pre-
determined value.
- 10 15 9. In a polishing machine comprising a
work-holding member, a plurality of polish-
ing members, means for causing relative
movement between the work and the polish-
ing members, means for supplying polish-
ing material to the polishing members, sep-
arate manually operated means for con-
trolling the supply of polishing material to
each of the polishing members, and an in-
dicator for each polishing member adapted
to indicate to the operator of said controlling
means when the friction between such polish-
ing member and the work reaches a pre-
determined value.
- 20 25

In testimony whereof, we have hereunto
set our hands.

WILLIAM TAYLOR.

FRANCIS WILLIAM PRESTON.
